SIGNALING DEVICE

Anthony J. Parissi, Cohoes, N. Y.

Application October 23, 1946, Serial No. 705,068

11 Claims. (Cl. 161—22)

1

My invention relates to signaling devices and particularly to devices of this character for awakening people at any predetermined time.

In my co-pending application, Serial No. 613,070, now U. S. Letters Patent No. 2,444,748, I have disclosed an alarm clock, specifically an electric alarm clock, by means of which two signals of different character are given in sequence. The first signal is the flashing of an electric lamp which may continue for any desired interval and which, if the lamp is burned out or any other defect prevents the giving of this first signal, is supplemented by an audible signal such as a buzzer.

The present invention relates to a signaling device in which the first signal given is a visible signal, as by the flashing of a lamp, and the second signal is given from a loud speaker of a radio, and in which the means for controlling these signals is of somewhat different character than that disclosed in my co-pending application aforesaid.

One of the objects of my invention is to provide a radio receiving device combined with a clock by means of which the timing of the signaling means is controlled. Another object is to provide a cabinet in which is combined a radio receiving means and a clock, and to which any available electric lamp may be connected by simply plugging the lamp wires into a receptacle in said cabinet. Another object is to provide a device of this character in which the radio may be used at any time independently of the signaling apparatus. Another object is to provide a device in which a table or other lamp may be connected thereto and which may be utilized to give the flashing signal, and also used at any time, except when the signaling apparatus is in actual operation, as a reading lamp independently of the signaling apparatus. Another object is to provide a signaling device comprising a radio receiving set for giving an audible signal and a lamp for giving a visible signal and means for controlling the operation of these signals in timed relation to each other. With these objects in view, my invention includes the novel elements and the combinations and arrangements thereof described below and illustrated in the accompanying drawings in which—

Fig. 1 is a front elevation view of my device;

Fig. 2 is a rear view of the device drawn to a substantially smaller scale;

Fig. 3 is a fragmentary perspective view of a portion of an electric clock with certain portions omitted and certain portions broken away in order clearly to show the particular parts thereof and the parts associated therewith which are pertinent to my invention;

2

Fig. 4 is a wiring diagram including, in a more or less diagrammatic manner, those portions of the clock mechanism which control the operation of the signaling circuits;

5 Fig. 5 and Fig. 6 show the relative positions of the contact fingers in closing the circuits for the first and second signals respectively; and

Fig. 7 is a fragmentary wiring diagram similar to Fig. 4 but illustrating a modification of the 10 lighting circuit.

Referring to the drawings, my device comprises a cabinet 1 containing a radio receiving set which may be turned on and off by means of the switch 2 and tuned by means of the knob 3 which moves the index 4 over the dial 5 which may be graduated in kilocycles, as well understood in the art, to indicate the frequency to which the set is tuned. 6 is the opening of a loud speaker, understood to be in the cabinet but not shown. 7 is an electric clock having a hand 8 which may be turned by the knob 9 to indicate the time at which the signal will be given. 10 is a knob for turning the alarm on or off and 11 is a table lamp, actuated by pulling the switch cord 12, and which may be plugged into the socket or outlet 13 on the back of the radio cabinet. As illustrated in Fig. 4, the outlet 13 would have three terminals and a three wire conductor would be required to connect the lamp 11 with the circuits in the cabinet in order to by-pass switch 12 when the alarm goes into operation and insure a positive operation of the lamp signal 11 irrespective of the position of switch 12. Projecting from the back of the cabinet 1 is a button 14 by turning which the hands of the clock may be set to the correct time. Also extending from the back of the cabinet 1 is the electrical conductor 15 having the usual plug 16 on the end thereof which may be inserted in any convenient outlet for connecting both the clock and the radio to a source of power.

Referring now more particularly to Fig. 3, 17 is the back of the face of the clock. 18 is a wide faced clock gear which is directly connected to the hour hand and which, therefore, makes one complete rotation every 12 hours. 19 is a narrow faced gear of the same diameter as the gear 18 and in mesh therewith so that it also makes one complete rotation in 12 hours. 20 is a gear which 45 is connected to the spindle or shaft carrying the alarm setting hand 8 (see Fig. 1). In mesh with the gear 20 is the gear 21 which is in mesh with the spur gear 22 on a shaft 23 which may be turned through suitable gearing (not shown) by 50 turning the button 9 to set the alarm at the desired time. The gear wheel 21 is provided with

an arcuate slot 25 therein which cooperates with a cam 26 on the rear side of the wheel 19. Since the wheel 18 revolves in the direction of the arrow shown thereon the wheel 19, in mesh therewith, revolves in the direction of the arrow shown on that wheel. The wheel 19 is coaxial with the wheel 21 and rides freely on its shaft 19' so that it may move toward and away from the wheel 21 and still remain in mesh with the wheel 18; the face of the wheel 18 being of substantial width to permit the aforesaid axial movements of the wheel 19 while maintaining it in mesh with the wheel 18. The cam 26 on that face of wheel 19 which is adjacent wheel 21 is provided with two steps 27 and 28 positioned to drop in the slot 25 in the wheel 21. The high point of the cam 26 normally rides in contact with the side of the gear 21 and the wheel 19 carrying cam 26 is normally urged towards wheel 21 by the lever 29, which is mounted on shaft 30, and the light helical spring 31 which is biased to hold the lever 29 in contact with the hub 32 on wheel 19.

From the foregoing, it will be apparent that the gears 20 and 21 are normally stationary except when the alarm is being set by turning the setting button 9.

It will be also apparent that, since the gear 19 makes one turn in every 12 hours, the cam 26 will be forced into the slot 25 once in every 12 hours. First the step 27 will drop into the slot 25 and, as the wheel 19 continues to rotate, step 28 will drop into the slot. As the wheel 19 continues to rotate, the cam 26 will be forced out of the slot and pushes the wheel 19 back to its normal position by the cooperation of the curved cam-like surface 33 with the end of the slot.

The wheels 19 and 21 with the slot 25 and cam 26 are also shown in Figs. 4, 5 and 6 in a more or less diagrammatic manner but, before passing to a detailed description of these last mentioned figures, it might be well to point out that, in Fig. 3 an armature or buzzer 34 having a clapper 35 associated therewith and adapted to strike the gong 36 is shown and may be used if desired. The armature 34 is always energized when the clock mechanism is connected to a source of power and, unless restrained, would vibrate continuously. It is normally held inoperative by means of the push-pull button 37 which projects through the back of the casing or cabinet 1 and has a projection 38 thereon which cooperates with the armature 34, when the button 37 is pushed in, to prevent vibration thereof. The armature is also restrained by the projection 38' on the lever 28 when in the position shown in Fig. 3. However, when the button 37 is pulled out, the armature or buzzer is then held inoperative only by the projection 38' on lever 28 so that, when the cam 26 drops into the slot 25 in wheel 21, as wheel 19 is moved towards wheel 21 by the lever 29 and spring 31, projection 38' moves away from the end of armature 34 and the armature automatically begins to vibrate and emit a buzzing sound or ring the gong if provided with the clapper 35.

Referring to Fig. 4 in connection with Fig. 3, it will be noted that a resilient finger 39 is provided with a button 40 of fibre or other insulating material which bears against the side of gear 19 which carries the cam 26. The finger 39 is mounted with fingers 41, 42, 43, and 44 on the back of the face 17 of the clock as shown in Fig. 4. Each of these fingers is electrically insulated from each of the other fingers by means of the insulating blocks 45 therebetween and the in-

sulating bushings 46 through which the means 47 for securing them together pass. The resilient finger 39 is provided with contacts 48 and 49 on opposite sides thereof; the finger 41 is provided with a contact 50 adapted to cooperate with the contact 48 on finger 39; the finger 42 is provided with a contact 51 adapted to cooperate with the contact 49 and, on the other side thereof, with a contact 52 adapted to cooperate with the contact 53 on the finger 43; 43 in turn being provided on the other side thereof with a contact 54 adapted to cooperate with the contact 55 on finger 44.

Normally, the gears 19 and 21 and the resilient fingers are in position shown in Fig. 4, while Fig. 5 shows the position of the fingers when the cam 26 has moved its first step into slot 25 in wheel 21, and Fig. 6 shows the position of the resilient fingers when cam 26 has moved its second step into the slot 25.

In Fig. 4, 56 and 57 are the main power lines to which the terminals 58 and 59 of the signaling device are connected when the plug 16 is inserted in a convenient outlet. 60 is the radio which is provided with the switch 2 for turning it off and on and the tuning means 3 which is regulated by the knob 3, shown in Fig. 1. It will be apparent that, by closing the switch 2, the radio 60 may be connected directly to the power lines 56 and 57. Thus, by closing or opening the switch 2, the radio may be operated at any time independently of the signaling mechanism. 11 is a table lamp, one terminal of which, when the lamp is plugged into the outlet 13, is connected permanently to the power line 56, and the other terminal may be connected with the other power line 57 by closing the switch 12 which closes a circuit through the conductors 61 and 62, and switch 10 which is a double pole, double throw switch, or its equivalent, for closing and opening the circuits, as shown in Fig. 4. It will be apparent from the foregoing that the lamp 11 may be used at any time in a normal manner when the switch 10 is in either the alarm "off" or the alarm "on" position.

When the alarm is set at the desired hour, the switch 10 may be moved to the alarm "on" position, but this does not in any way, so long as the alarm is not in actual operation, interfere with the normal use of the radio or the lamp 11. Thus, the lamp may be turned off and on by means of the switch 12 although a somewhat different circuit is used when the switch 10 is in the "on" position than when it is in the "off" position. When the switch 10 is in the "on" position, the circuit through the lamp is through switch 12, conductor 61, finger 41, through the contacts 48 and 50, finger 39, conductor 64, switch 10 and conductor 63 to the main power line 57. Obviously, the movement of the switch 10 to the alarm "on" position does not in any way affect the operation of the switch 2 to turn the radio off and on.

Ordinarily, upon retiring, the table lamp switch 65 would be turned to the "off" position to extinguish the light but, whether or not it is extinguished, it will begin to flash, as will be described below, when the first step of cam 26 drops into slot 25. When this occurs at the appointed hour, and the switch 10 is in the alarm "on" position, the fingers are as shown in Fig. 5 and a circuit through the lamp 11 is established as follows:

The connection between contacts 48 and 50 is broken and a connection is established between contacts 49 and 51, as shown in Fig. 5, thus the

circuit through the lamp control switch 12 is opened and switch 12 is by-passed. Starting with power line 56 adjacent the lamp 11, the current flows through the lamp, conductor 65, switch 10, conductors 66 and 67 through the coil 68 which surrounds the bimetallic element 69 in the thermostatic switch 70, and thence through conductor 71, finger 42, contacts 49 and 51, finger 39, conductor 64, switch 10 and conductor 63 to power line 57. When the thermostatic switch 70 is in this position the light 11 is not lighted because sufficient current is not flowing through the above circuit due to the high resistance of the coil 68 in the thermostatic switch. However, the current flowing through the coil 68 heats the thermostatic element 69 causing it to warp upwardly and close the contact points so that a circuit between lamp 11 is then established through conductor 65, the short leg 72 of switch 10, conductors 66 and 67, the contacts of switch 10, directly through the thermostat element 69, conductor 71, finger 42, contacts 49 and 51, conductor 64, the long leg 73 of the switch 10 and conductor 63 to power line 57; and the lamp is thus lighted.

However, the closing of the contact points of switch 70 shunts the heating coil 68 around the thermostat element 69 which causes the element 69 to cool and flex so that the switch 70 is opened whereupon the cycle is repeated. Thus, an intermittent flashing of the lamp 11 continues so long as the last mentioned circuits are maintained. While the thermostatic element does not entirely break the circuit through the lamp, since some small amount of current is always flowing through the high resistance coil 68, it does, in effect, break the "lighting" circuit insofar as the illumination of the lamp is concerned, and I have therefore referred to its function as that of making and breaking an electrical circuit.

When the second notch or step of the cam 26 drops into the slot 25 the fingers are then in the position shown in Fig. 6. In this position fingers 39, 42, 43 and 44 are all electrically connected together with the following result:

When finger 44 is electrically connected, as in Fig. 6, to finger 39, a new circuit is established through the lamp 11 which by-passes thermostatic switch 70 and connects lamp 11 directly to the power lines so that an uninterrupted lighting of said lamp occurs. Thus, starting from the power line 56 adjacent lamp 11, current flows through lamp 11, conductor 65, the short leg 72 of switch 10, conductors 66 and 74, finger 44 through contacts 55, 54, 53, 52, 51 and 49 to finger 39, thence through conductor 64 through the long leg 73 of switch 10 and conductor 63 to power line 57.

Simultaneously with the uninterrupted illumination of lamp 11, another circuit is established through the radio receiver 60 as follows:

Starting at the point where conductor 75 contacts power line 56, current flows through the conductor 75 through the radio receiver 60, through the conductor 76 which by-passes radio control switch 2 to finger 43, thence through contacts 53, 52, 51 and 49 to finger 39 which is connected to conductor 64, thence through conductor 64 and the long leg 73 of switch 10 through conductor 63 to power line 57. Thus, if the radio receiver is tuned to receive a program or signals from a certain station, the program or signals will be heard through the loud speaker of the receiver.

If the device is used as an alarm clock, the light may be extinguished and the program shut

10 off by moving the switch 10 to the "off" position whereupon the light 11 may be controlled by means of the switch 12. Should it happen that the signaling means has been set for operation and no one is present to shut off the signal by moving switch 10 as aforesaid, the cam 26, due to the rounded face 77 thereon will, in a short time, ride out of the slot 25 and restore the parts to their normal position shown in Fig. 4, thus automatically shunting off the signals.

With the arrangement as illustrated and described in connection with Fig. 4, a three-wire cable is required if the lamp 11 is to be controlled by a switch 12 thereon because it is necessary to have two separate circuits, having one common wire leading to the lamp 11 so that it is possible both to control the lamp 11 through the switch 12 and also to control the lamp 11 by means of a circuit which by-passes switch 12.

20 Where an ordinary two-wire cable is used to connect lamp 11 to an outlet 13 in the casing 1, a minor change in the lamp circuit is required as shown in Fig. 7, and it is also desirable to provide the switch 10 with a neutral or "off" position.

25 The only change required in the circuit is to eliminate the switch 12 and to connect the conductor 61 to the conductor 65 as shown at 78 in Fig. 7. With this circuit the lamp 11 may be lighted by turning the switch 10 to the "light" position so

30 that a circuit is formed from power line 56 through the lamp, conductor 61, conductor 62, the long leg 73 of switch 10 and conductor 63 to power line 57. To extinguish lamp 11, switch 10 is merely turned to the "off" position.

35 When the fingers are in the position shown in Fig. 4 and the switch 10 in Fig. 7 is in the alarm "on" position, no current is flowing through the conductor 66 because one of the current paths leading from conductor 66 is through conductor

40 74 to finger 44 where it terminates, and the other path is from conductor 66 through conductor 67, heating coil 68 on thermostatic switch 70 and through conductor 71 to finger 42 where it ends. However, when the first notch of cam 26 drops

45 into the slot 25, thus connecting finger 42 with finger 39, a circuit through lamp 11 and through the thermostatic switch, which causes an intermittent flashing of lamp 11, is established as described above. When the second step of cam 26

50 drops into slot 25, thus arranging the switch fingers as illustrated in Fig. 6, the radio receiver is connected to the power lines and the lamp 11 is connected directly to the power lines to produce an uninterrupted lighting thereof, as described above.

55 From the foregoing, it will be apparent that the lamp alone may be used as a signal by merely tuning the radio receiver so that no signal is received therefrom when said receiver is connected to the power lines. Furthermore, the radio receiver may be used alone as a signal by merely removing the lamp 11 from its socket; the buzzer or gong may be used alone in place of the lamp, or with the lamp or the radio, or with both.

60 While I have described my invention in its preferred embodiment, it is to be understood that the words which I have used are words of description rather than of limitation and that changes, within the purview of the appended claims, may be made without departing from the true scope and spirit of my invention in its broader aspects.

What I claim is:

1. A signaling device comprising a cabinet, a

radio receiver and an electric clock mechanism therein, means for connecting said clock mechanism to a source of power, a manually actuated switch on said cabinet for connecting said receiver to said source of power when said clock mechanism is so connected, an outlet on said cabinet adapted to connect an electric lamp to said source of power when said clock mechanism is so connected, a thermostatic switch in said cabinet for automatically making and breaking an electrical circuit, and clock controlled means for establishing at a predetermined time an electric circuit from said source of power through said thermostatic switch and through said lamp, when connected, to produce an intermittent flashing thereof and, after a predetermined interval, establishing a circuit by-passing said thermostatic switch from said source of power through said lamp to effect an uninterrupted lighting thereof.

2. A signaling device comprising a cabinet, a radio receiver and an electric clock mechanism therein, means for connecting said clock mechanism to a source of power, a manually actuated switch on said cabinet for connecting said receiver to said source of power when said clock mechanism is so connected, an outlet on said cabinet adapted to connect an electric lamp to said source of power when said clock mechanism is so connected, a thermostatic switch in said cabinet for automatically making and breaking an electrical circuit, and clock controlled means for establishing at a predetermined time an electric circuit from said source of power through said thermostatic switch and through said lamp, when connected, to produce an intermittent flashing thereof and, after a predetermined interval, establishing a circuit from said source of power through said radio receiver and also a second circuit from said source of power through said lamp by-passing said thermostatic switch to produce an uninterrupted lighting of said lamp.

3. In a signaling device, the combination with a casing, of a clock mechanism therein including a first wheel which rotates once in twelve hours, a second wheel coaxial with said first wheel, means on which said wheels may rotate independently of each other and providing relative axial movements of said wheels towards and away from each other, means normally urging said wheels towards each other, clock controlled means controlling the axial spacing of said wheels, an electric lamp, a thermostatic switch adapted automatically to make and break an electric circuit, a switch for actuating said lamp, means adapted to connect said device to a source of power, means cooperating with one of said wheels for normally maintaining an electric circuit, including said lamp switch and said lamp and said source of power when said device is connected thereto; whereby said lamp normally may be lighted and extinguished by said lamp switch, means operable by a first, relative, axial movement of said wheels for breaking said circuit and establishing a second circuit from said source of power through said thermostatic switch and said lamp for causing an intermittent flashing of said lamp, and means operable by a second, relative, axial movement of said wheels for establishing a second circuit from said source of power to said lamp and by-passing said thermostatic switch to effect an uninterrupted lighting of said lamp.

4. A signaling device comprising a casing, a

clock mechanism therein, means for connecting said mechanism to a source of electric power, an outlet on said casing adapted to connect an electric lamp to said source of power when said clock mechanism is so connected, a switch on said casing for opening and closing the circuit from said source of power to said lamp for controlling the same, a thermostatic switch adapted automatically and intermittently to make and break an electric circuit, clock controlled means for establishing a first circuit from said source of power through said thermostatic switch and said lamp to cause an intermittent flashing of said lamp, and, after a predetermined interval, establishing a second circuit from said source of power through said lamp by-passing said thermostatic switch to effect an uninterrupted lighting of said lamp, and means for setting said clock controlled means to effect the establishment of said first circuit at a predetermined time.

5. A signaling device comprising a casing, a clock mechanism therein, means for connecting said mechanism to a source of electric power, a three terminal outlet on said casing adapted to connect an electric lamp having a switch thereon for controlling the same to said source of power, when said clock mechanism is so connected, by one circuit including said switch and also by a second circuit by-passing said switch, a thermostatic switch adapted automatically and intermittently to make and break an electric circuit, a switch on said casing for setting said signal device for operation when in one position and rendering it inoperative when in another position; said switch in either of said positions normally closing an electric circuit from said source of power through said lamp and the switch controlling the same; whereby said lamp may normally be controlled by said controlling switch; clock controlled means for establishing at a predetermined time a circuit from said source of power to said lamp through said thermostatic switch and by-passing said lamp controlling switch; whereby to effect an intermittent flashing of said lamp; and, after a predetermined interval, establishing a second circuit from said source of power through said lamp by-passing said thermostatic switch to effect an uninterrupted lighting of said lamp, and means for setting said clock controlled means for operation at a predetermined time.

6. A signaling device comprising a casing, a clock mechanism therein, means for connecting said mechanism to a source of electric power, an outlet on said casing adapted to connect an electric lamp to said source of power when said clock mechanism is so connected, a switch on said casing for opening and closing the circuit from said source of power to said lamp for controlling the same, a thermostatic switch adapted automatically and intermittently to make and break an electric circuit, a radio receiver in said casing, a switch for controlling said receiver at all times when said clock mechanism is connected to said source of power, clock controlled means for establishing a first electric circuit from said source of power through said thermostatic switch and said lamp to effect an intermittent flashing of said lamp and, after a predetermined interval, establishing a second circuit from said source of power through said lamp by-passing said thermostatic switch to effect an uninterrupted lighting of said lamp and also a third circuit from said source of power through said radio receiver by-passing the radio receiver controlling switch,

and means for setting said clock controlled means for operation at a predetermined time.

7. In a signaling device including a clock for controlling the operation thereof, the combination with a wheel driven by said clock, of a normally stationary wheel having manually actuated means cooperating therewith for turning said stationary wheel to set said signaling device for operation at a predetermined time, means normally maintaining said wheels in fixed, axially spaced relation to each other, means for effecting a relative axial movement of said wheels at the time said signaling device is set for operation and, after a predetermined interval, a second relative axial movement of said wheels, an electric lamp, a thermostatic switch adapted automatically and intermittently to make and break an electric circuit, a first switch actuated by the first relative axial movement of said wheels adapted to close an electric circuit from a source of power through said lamp and said thermostatic switch for effecting an intermittent flashing of said lamp, and a second switch actuated by the second relative axial movement of said wheels adapted to establish a second circuit from said source of power through said lamp by-passing said thermostatic switch to effect an uninterrupted lighting of said lamp.

8. A signaling device comprising a casing, an electric clock mechanism therein, means for connecting said clock mechanism to a source of power, an outlet on said casing adapted electrically to connect a signaling device to said source of power when said clock mechanism is so connected, a switch in said casing for automatically and intermittently making and breaking an electric circuit, a first clock controlled means for electrically connecting said source of power to said outlet through said switch; whereby an intermittent source of power is provided at said outlet and said signaling device, when connected to said outlet, will give an intermittent signal, a second clock controlled means actuated by said clock after the lapse of a predetermined interval following the actuation of said first clock controlled means for connecting said outlet directly to said source of power; whereby said signaling device, when connected to said outlet, will give an uninterrupted signal; and means for setting said clock controlled means for operation at a predetermined time.

9. A signaling device comprising a casing, an electric clock mechanism therein, means for connecting said clock mechanism to a source of power, an outlet on said casing adapted to connect an electric lamp to said source of power when said clock mechanism is so connected, a first, manually-actuated switch for controlling the flow of current to said outlet at all times when said signaling device is not in actual operation, a second switch for automatically and intermittently making and breaking an electric circuit, a first clock controlled means for electrically connecting said outlet to said source of power through said second switch and by-passing said first switch; whereby said lamp, when connected to said outlet, will be intermittently lighted and extinguished; and a second clock controlled means actuated by said clock upon the expiration of a predetermined interval after the actuation of said first clock controlled means for electrically connecting said outlet directly to said source of power; whereby said lamp, when connected to said outlet, will be uninterruptedly lighted.

10. A signaling device comprising a casing, an electric clock mechanism in said casing, means for connecting said clock mechanism to a source of power, a radio receiver in said casing, a first manually operable switch for connecting said receiver to said source of power when said clock mechanism is so connected, a vibrating element normally energized when said clock mechanism is connected to a source of power for producing an audible signal, a clock-controlled second switch for connecting said receiver to said source of power, clock-controlled means normally holding said vibrating element inoperative and releasing it at a predetermined time, manually operable means for optionally holding said vibrating element inoperative or releasing the same to be held by said clock controlled means and released thereby, manually operable means for optionally rendering said clock-controlled second switch operative or inoperative to connect said receiver to said source of power, and manually operable means for setting said clock-controlled means for holding said vibrating element inoperative to release said vibrating element at a predetermined time, and said clock-controlled second switch to connect said receiver to said source of power at a predetermined time; whereby, when it is desired that said device give an audible signal at a time when no radio program is being broadcast, said vibrating element may be utilized instead of said radio receiver.

11. A signaling device comprising a casing, an electric clock mechanism therein, means for connecting said clock mechanism to a source of power, a radio receiver in said casing for normally giving an audible signal, a first manually controlled switch for connecting said receiver to said source of power when said clock mechanism is so connected, a vibrating element normally energized when said clock mechanism is connected to a source of power for giving another audible signal, clock-controlled means normally holding said vibrating element inoperative and releasing it at a predetermined time, a second switch controlled by said clock for connecting said receiver to the source of power when said clock is so connected to give a signal at a predetermined time, manually operable means for preventing the operation of said vibrating element when it would otherwise operate upon a release thereof by said clock-controlled means, manually operable means for setting said clock-controlled means to release said vibrating element and also to close said second switch at a predetermined time, and clock actuated means for automatically stopping the operation of said vibrating element and opening said second switch after the expiration of a predetermined interval.
